UNITED STATES PATENT OFFICE.

JACOB H. COFFMAN, OF PHILADELPHIA, PENNSYLVANIA.

GAME.

1,223,256.

Specification of Letters Patent. Patented Apr. 17, 1917.

Application filed August 22, 1916. Serial No. 116,278.

To all whom it may concern:

Be it known that I, JACOB H. COFFMAN, a citizen of the United States, residing at Philadelphia, in the county of Philadelphia and State of Pennsylvania, have invented 5 certain useful Improvements in Games, of which the following is a specification, reference being had therein to the accompanying drawing.

10 This invention relates to improvements in games, one object of the invention being the provision of a game to be played with marbles and which is so constructed and arranged as to require skill to play and secure a high score, and which is amusing.

A further object of this invention is the provision of a game in which a vertical plate is provided with a plurality of apertures through which marbles are to be projected 15 in combination with a deflecting means mounted at the rear thereof, the object of which is to change the course of the marble in passing through any one of the openings and to direct the same rearwardly 20 through said openings.

In the accompanying drawings:—

Figure 1 is a front elevation of the game apparatus.

Fig. 2 is a rear elevation thereof.

30 Fig. 3 is a top plan view thereof.

Fig. 4 is a cross section taken on line 4—4 of Fig. 3.

Fig. 5 is a section taken on line 5—5 of Fig. 3.

35 Fig. 6 is a detail view of the bell clapper and mounting.

Referring to the drawings, the numeral 10 designates the main supporting member 10 which is made of a flat piece of material, 40 either wood, cardboard, or paper fiber, as may be found desirable, or the same may be made of metal.

Upon the lower edge of this board are provided a plurality of arched openings or 45 notches 11, here shown as indicating, beginning with the numeral 5, multiples of 5, up to 25.

Also provided in the lower edge of the member 10 are a plurality of vertical slots 50 12 for the reception of the hook terminals 13 of the triangular marble guiding members 14 which are disposed to project forwardly from the member 10 and coöperate so as to provide converging guideways to 55 each of the respective openings 11.

Attached to the rear of the member 10

by means of the hook terminals of the outer triangular members are the connecting portions 14' of the deflecting member 16.

This member is preferably made of a 60 strip of sheet metal and is bent, as shown in top plan, substantially U-shaped.

Provided in the lower edge of the deflecting member adjacent the respective outer openings 11 are slots 17, while attached to 65 the rear of the member 15 adjacent such openings are the bells 19.

Attached also to the member 16, one to each of the bells, are the resilient strips 20, 70 each one of which is provided with the projection 21 and coöperates with the strip 20 to form a bell clapper.

Mounted upon the forward portion of the member 10 above the respective outer openings are the indicator dials 22 having printed thereupon multiples of 5 up to a predetermined number, and as two can play the game, there are two of these members, one to each player, to prevent confusion.

The indicating pointer 23 is made from a 80 single strand of wire and is provided with the hook terminal 24 and with the intermediate integral finger engaging loop 26.

In playing the present game, marbles are employed, and after the member 10 is placed 85 in an upright position, being supported by means of the triangular guiding members and the deflecting member so as to be steady at all times, such members constituting feet for the member 10, the players mark off a 90 line approximately two to three feet from the front surface of the member 10, and each player is given five or ten marbles to play with.

It is the object of the game to cause a marble to enter one of the openings, as for instance 5, strike the deflecting member 16, and return through one of the other openings at the right, and as long as such return is made the marble is in play, the total of 95 the numbers above the openings through which the marble passes being scored and indicated upon the respective player's indicator. Should a player shoot a marble through the entrance 5 and at the same time 100 ring the bell his amount is doubled, that is he is credited with 10 and, if the same marble makes its exit through the entrance or opening 25 he is credited with 35 but should he ring when coming out of the gate 25 as is 110 often the case, then he is credited with 60 by such play.

Should the marble fail to return or miss an opening in its forward projection, the same is out of play.

Any total may be a game, as for instance, 5 one hundred to five hundred, and the first player to reach that amount is the winner.

What I claim as new is:—

1. A game apparatus, including a relatively flat strip having a plurality of openings through the lower edge thereof, a deflecting member attached to the rear of such member and in the path of the openings, an audible alarm carried by the deflecting member, and means for actuating said alarm also 10 carried by said member and disposed in the path to be engaged by a projectile.

2. A game apparatus, including a relatively flat strip having a plurality of openings through the lower edge thereof, a deflecting member attached to the rear of such 20

member and in the path of the openings, and a plurality of guide forming members attached to the front face of said strip, two of said members coöperating to form a projectile guide for each opening. 25

3. A game apparatus, including a relatively flat strip having a plurality of openings through the lower edge thereof, a deflecting member attached to the rear of such member and in the path of the openings, an audible alarm carried by the deflecting member, means for actuating said alarm also carried by said member and disposed in the path to be engaged by a projectile, and a plurality of guide forming members attached to 30 the front face of said strip, two of said members coöperating to form a projectile guide for each opening. 35

In testimony whereof I affix my signature.

JACOB H. COFFMAN.
